UNITED STATES PATENT OFFICE.

MILFORD T. GOSS, OF DENVER, COLORADO.

WATER-TUBE BOILER.

SPECIFICATION forming part of Letters Patent No. 774,419, dated November 8, 1904.

Application filed March 18, 1904. Serial No. 198,718. (No model.)

To all whom it may concern:

Be it known that I, MILFORD T. Goss, a citizen of the United States, residing at Denver, in the county of Denver and State of Colorado, have invented a new and useful Water-Tube Boiler, of which the following is a specification.

This invention relates to improvements in boilers, and has for its object to prevent a deposit of sediment by increasing the rapidity of circulation of the water considerably above the speed at which the water moves under ordinary circumstances when subjected to the action of heat in the usual manner.

15 In steam-boilers it is disastrous to use water containing a large percentage of salts or other matter which would deposit on the boiler shell or tubes and by baking form a thick crust which would retard the passage of heat and at the same time serve to permit the burning of the shell or tubes, and in many cases under such conditions the use of water-tube boilers particularly is wholly impractical.

20 The principal object of the invention, therefore, is to overcome this difficulty by greatly accelerating the speed of travel of the water by injecting into the boiler a jet or jets of steam under high pressure, these jets being directed against and into the boiler at points 25 where the sediment will be most likely to accumulate and at the same time in such manner as to direct the water into its natural channel.

25 A further object of the invention is to provide for the cleaning of the boiler while in operation and under the usual pressure by arranging for the admission of jets of higher-pressure steam at points where the sediment accumulates and adjacent to the lower blow-off holes or pipes.

With these and other objects in view, as will more fully hereinafter appear, the invention consists in certain novel features of construction and arrangement of parts herein- 45 after described, illustrated in the accompanying drawings, and particularly pointed out in the appended claims, it being understood that various changes in the form, proportions, size, and minor details of the structure may

be made without departing from the spirit or 50 sacrificing any of the advantages of the invention.

In the accompanying drawings, Figure 1 is a longitudinal sectional view of a steam-boiler furnace embodying the invention. Fig. 2 is 55 a detail transverse section of a portion of the rear header.

Similar numerals of reference are employed to indicate corresponding parts throughout both figures of the drawings. 60

The boiler is supported in the usual manner and is provided with a front header 1 and a rear header 2, these being connected by water-tubes 3, connected in the usual manner to the sheets forming the walls of the headers. 65 Above the headers and connected thereto in the usual manner is a drum 4, having at its rear and lowermost end a blow-off 5, similar blow-offs 6 being formed on the bottom sheets of both of the headers. 70

The outer sheet of the rear header is provided with a plurality of hand-holes 7, disposed in alinement with the several water-tubes, and covering each opening is a hand-hole plate 8, the hand-hole plates being of 75 the usual oval or elliptical type in order to permit the removal of each through the openings of said covers. The hand-hole plate is held in position by a bridge or binder 10, having an opening for the passage of a hollow 80 bolt 11, one end of which is threaded and screwed in a threaded opening formed at the central portion of the plate. The opposite end of the hollow bolt is also threaded and receives a nut 12, which bears against the 85 outer end of the bridge or binder, and by adjusting which the hand-hole plate may be drawn tightly against its seat. The threaded opening in the plate 8 also receives a threaded section or nipple 14, disposed in axial alinement with the water-tube and having, preferably, a nozzle-shaped end in order not to interfere with the movement of the current of water entering the tube. In practice one of these tubes and tube connections are arranged 90 at the rear header 2 and in direct alinement with each of the water-tubes of the boiler, the number of tubes dependent on the size 95

and horse-power of the boiler. The several tubes 11 are connected to a source of steam-supply at a much greater pressure than the low-pressure boiler into which the steam is to 5 be introduced through tubes 11.

In addition to the several connections in alignment with the water-tubes an additional injecting-pipe is connected at 15, this being the front end of the drum, and similar connections are made at the opposite sides of the lower portion of the headers and adjacent to the blow-off openings 6.

With a boiler of this character it is possible to use water carrying a very large percentage of salts or other matter which would 15 in an ordinary boiler form a deposit and cause the wearing out of the boiler shell and tube or tubes, the jets of high-pressure steam accelerating the natural circulation of the water and by keeping it in a constant state of motion prevent a deposit, and any matter which may be precipitated will be instantly taken up and carried along with the current of water. The sediment will have a tendency 20 to accumulate at the lower rear end of the drums and at the bottom of the two headers, and from time to time it is necessary to open the blow-off cock and permit the escape of sediment, the jet of steam directed at the 25 front end of the drum and the jets directed into the opposite sides of the headers serving to prevent the formation of a scale and insuring the complete discharge of all of the foreign matter at points adjacent to the blow-off cocks each time the latter are opened.

The boiler illustrated is of the water-tube type, and the jets of high-pressure steam will act more effectively in accelerating the current of water in boilers of this type than in 40 fire-tube boilers; but it is to be understood that the same principle may be applied in connection with boilers of any type by connecting same to the source of the higher-pressure steam by the usual means of pipe connections without departing from the invention, (and any and all benefits arising from 45 increased circulation as a result of the application of this principle of introducing higher-pressure steam into a lower-pressure boiler by 50 means of these tubes and tube connections or

by the usual pipe connections are a part of this invention.)

Having thus described the invention, what is claimed is—

1. The herein-described method of preventing the formation of deposits in boilers, said method consisting in introducing jets of high-pressure steam into the water-space of the boiler at points below the water-line thereof. 55

2. The herein-described method of preventing the accumulation of sedimentary deposits in boilers, said method consisting in forcing jets of high-pressure steam into said boiler in positions to accelerate the natural circulation of water in the boiler. 60

3. The herein-described method of preventing the accumulation of sedimentary deposits in water-tube boilers, said method consisting in directing jets of high-pressure steam into the ends of the tubes in a direction to accelerate the flow of water through said tubes. 65

4. The herein-described method of preventing the accumulation of sedimentary deposits in boilers, said method consisting in introducing jets of steam under high pressure into 70 said boilers at points adjacent to the blow-off openings thereof.

5. In water-tube boilers, the combination with headers having hand-hole openings, of hand-hole plates, and hollow bolts serving to hold the plates in position, said bolts serving also for the passage of jets of high-pressure steam to the boiler. 75

6. The combination with a water-tube boiler including headers having hand-hole openings 80 opposite the tubes, of hand-hole plates having threaded openings, binders, hollow bolts extending therethrough and connected to the plates, a nut for each of the bolts, and a nipple connection in alignment with the hollow 85 bolt and serving to direct the jet of steam in the direction of the water-tube with which it is in alignment.

In testimony that I claim the foregoing as my own I have hereto affixed my signature in 90 the presence of two witnesses.

MILFORD T. GOSS.
